UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed March 7, 1923. Serial No. 623,322.

To all whom it may concern:

Be it known that I, GEORGE CLAUSING, a citizen of the United States, and a resident of the city of Portsmouth, in the county of 5 Scioto and State of Ohio, have invented certain new and useful Improvements in Lasts, of which the following is a specification.

My invention relates to an improvement in lasts of the divided or hinged type, i. e., 10 to lasts comprising a toe part and a heel part which are attached to each other in such a manner that the two parts of the last may be given a relative movement to shorten or to extend the last as the case may be, an 15 object of the invention being the provision of a last of this type wherein lost motion or wobble of the last parts when extended is prevented.

In a last of the divided type it is usual to 20 divide the block from which the last is made into two parts by a saw cut to form a socket in one part of the last and a knuckle on the other portion thereby providing a bearing about which the last parts move when the 25 last parts are being changed from an extended position to a shortened position and vice versa. In order that the last parts may be held against separation it is usual to connect them together by a link attached 30 to the two last parts by pins or other suitable means (in the present construction spring pins are used), this link lying within a longitudinally extending groove or slot with which the last parts are provided.

It has been found in practice with lasts 35 of this type that there is more or less side play or lost motion between the two parts of the last when the last is extended although the last parts are held against separation under more or less tension, the distance between the spring pins by which the link is attached to the two last parts of the last being slightly greater than the distance 40 between the holes in the ends of the link which receive these pins to form a "draw" in holding the two parts firmly together.

In the accompanying drawings a last embodying my improved construction has been illustrated,—

50 Fig. 1 being a part sectional elevational view of the same;

Fig. 2 a section on the line 2—2 of Fig. 1; and

55 Fig. 3 a section on the line 3—3 of Fig. 2. Referring to the drawings in detail,—1

and 2 designate respectively, the fore part and heel part of a last embodying my improved construction, the two parts of the last being divided along the lines 3 and 4 to form a knuckle 5 and socket 6 providing 60 a bearing about which the two parts of the last are moved as the last is extended or collapsed.

The last parts are connected by a link 7 extending longitudinally of the last parts 65 and lying in a groove or slot 8 in the two parts of the last, one end of the link being connected to the toe part by a spring pin 9 and the other end being connected to the heel part by a spring pin 10. These pins as is 70 customary, are so located that a line drawn through their centers falls below the center of the knuckle 5 when the last is extended and above this point when the last is collapsed. 75

The link in the present case comprises two metal members 11 and 12 lying side-by-side or it may be any suitable link so shaped to fill the slot, the face of these members next the walls of the slot or groove 8 being bulged as indicated at 13 and 14 so as to fill the groove or slot transversely of the last while the two ends of these members are contracted so as to permit the resilient pins 9 and 10 to yield in the operation of the last. 80 85

It will be seen, therefore, that this construction provides a last structure wherein relative side motion of the last parts is effectively prevented by the particular form of link employed, whether two-piece, solid, or tube with flattened ends, this link as above pointed out filling the groove 8 which receives the link without sacrificing the resiliency of the pins 9 and 10. 90

I claim:

1. In a last, the combination of a fore part and a heel part each of which is provided with a longitudinally extending groove, a rigid link for attaching the last parts to each other to prevent their separation and comprising two plates lying side by side, spring pins passing through said plates for attaching the rigid link to the last parts, said plates intermediate said pins being of increased cross section relatively to the remaining portions of the plates, to substantially fill the said longitudinally extending grooves in the toe and heel parts of the last. 100 105

2. In a last, the combination of a fore part and a heel part each provided with a longi- 110

tudinally extending groove, a rigid link for attaching the last parts to each other, spring pins passing through the ends of said link for attaching the link to the last parts, said link comprising two plates lying side by side and in contact with each other throughout their length, that portion of said plates between said pins extending transversely

beyond the point of attachment of the plates to the pins, to substantially fill the said longitudinal grooves in the last parts, said plates engaging the walls of said grooves for substantially their entire length. ¹⁰

This specification signed this 1 day of March, 1923.

GEORGE CLAUSING.
